UNITED STATES PATENT OFFICE.

WILLIAM P. CLIFFORD, OF BARNARD, NEW YORK, ASSIGNOR, BY MESNE ASSIGNMENTS, TO UNITED SHOE MACHINERY CORPORATION, OF PATERSON, NEW JERSEY, A CORPORATION OF NEW JERSEY.

FOLDING AND TAPE-APPLYING MACHINE.

1,338,000.

Specification of Letters Patent. Patented Apr. 27, 1920.

Application filed November 2, 1914. Serial No. 869,850.

To all whom it may concern:

Be it known that I, WILLIAM P. CLIFFORD, a citizen of the United States, residing at Barnard, in the county of Monroe and State 5 of New York, have invented certain Improvements in Folding and Tape-Applying Machines, of which the following description, in connection with the accompanying drawings, is a specification, like reference 10 characters on the drawings indicating like parts in the several figures.

This invention relates to machines for operating upon articles of pliable material which are designed to be used in the manufacture 15 of boots and shoes and is herein illustrated as embodied in a machine for folding the margin of a button fly and applying adjacent to the folded margin a strip of strengthening material.

For convenience in describing the invention the strip of strengthening material will be referred to as a piece of tape and the article to which it is applied as a button fly, but it should be understood that the nature 20 of the strengthening strip and the particular article to which it is applied are immaterial so far as the broader aspects of the invention are concerned.

It is customary to fold the margin of a 25 button fly so as to produce a finished edge and to apply to the under side adjacent to the margin thereof a piece of tape or similar material for the purpose of strengthening the edges of the buttonholes which are subsequently formed in said button fly.

According to the present invention novel and improved means are provided for simultaneously folding the margin of sheet material and laying a piece of tape or other 30 flexible reinforcing element contiguous to but independent of the folded margin. In the illustrated machine a combined feed member and fold presser feeds both the sheet material which is to be folded and the tape; and a stationary guide member is provided for directing the tape into the desired position.

It is sometimes desirable to lay the tape directly alongside the folded margin and at 35 others to lay it spaced therefrom. Another feature of the invention comprises means for guiding the tape or other flexible rein-

forcing element, into place adjacent to the margin of a piece of material, and means whereby said guiding means may be adjusted to vary the spacing of said element from 55 said margin.

These and other features of the invention including certain details of construction and combinations of parts will be described 60 in connection with certain illustrative machines and pointed out in the appended claims.

Referring now to the accompanying drawings, 65

Figure 1 is a perspective of a combined folding and tape applying machine in which the present invention is embodied;

Fig. 2 is a perspective of a button fly with a piece of tape in place; 70

Fig. 3 is a perspective showing the rear and under side of the member which serves both to determine the line of fold and to guide the tape into place;

Fig. 4 is a perspective of a modified machine. 75

Referring first to Figs. 1 and 2, the mechanism for folding the margin of the button fly is substantially identical with that of the folding machine of the application of 80 Glass, Serial No. 790,892, now Patent No. 1,281,555. Taking this up briefly, the material is fed over the bed or support 1 with the margin which is to be folded over extending upwardly upon the suitably curved 85 face of a block 3 and lying between said block and a gage 5 having a portion which extends outwardly over the block 3, said extending portion being curved on its under side so as to guide the margin of the material against the curved face of the block. It will be noted, too, that this gage limits the upward extent of the turned-up margin and thereby the width of the fold which is to be made. In the machine of the patent 90 95 the material next passes a knife which may be caused to slit the margin if so desired. The knife, however, has not been shown since, with the tape applying mechanism presently to be described, it is held in its inoperative position. After passing between the block 3 and the gage 5 the margin passes over a folding finger which thereupon rises from beneath the bed 1 and

bends said margin about the edge of the creaser 9; said folder acting to bend said margin something more than 90° so that when the material has been fed forward 5 another step the margin will be pressed down upon the body of the material by the hammer or presser 11. This presser holds the folded margin against an anvil 13 for an interval, and during this interval the 10 hammer and anvil are given a movement to the left, thus feeding the material one step. The hammer then rises, and both hammer and anvil return to the position shown. With this mechanism the material 15 is fed progressively and intermittently, and the margin is similarly folded. The gage 5 has a finger piece 15 by pressure upon which it may be raised, its normal position being maintained by a spring 17. The creaser 20 9 may be raised by a finger piece (not shown) against the force of a spring-pin 19. The creaser is also held in its angular position by resilient means (not shown) so that it may swing toward and from the 25 line of fold to accommodate thick portions of the material.

The mechanism which has been briefly indicated above will not be further described since the details of its construction have 30 been set forth and claimed in said patent.

Referring now to Fig. 2, a button fly blank is indicated at 100 and a piece of tape pressed into place at 200. This tape is supplied to the trade in rolls, being covered on 35 one side with a coating of adhesive material. It is, therefore, necessary merely to guide the tape into place and then to press it down so that it will adhere to the leather or other material of which the button fly is made.

40 In the illustrative machine the creaser 9 is so formed as to serve the added purpose of guiding the tape into place on the button fly. Referring now to Fig. 3, this creaser comprises a vertical stem 109 and a somewhat U-shaped portion the legs of which are substantially horizontal, the lower leg being offset from a vertical plane which coincides with the rear face (the face presented in Fig. 3) of the upper leg. On the under 45 side of the lower leg is formed a groove 21; and from that side of the leg which faces the oncoming work extend two guiding fingers 23 whose inner faces register respectively with the sides of the groove. The 50 inner side 25 of the groove 21 is spaced from the operative end 209 of the creaser a distance equal to or greater than the width of the folded margin of the material so that the tape will be laid alongside said margin. The 55 inner side 25 of the groove 21 is spaced from the operative end 209 of the creaser a distance equal to or greater than the width of the folded margin of the material so that the tape will be laid alongside said margin.

60 The tape is supplied from a reel, not shown, from which it passes through a slot or equivalent opening in a member 27 herein shown as a strip of metal bent twice at right angles and adjustably fastened to a stationary 65 part of the machine by a screw 29 which

passes through a slot 31. The groove in the bottom of the combined fold-creaser and tape-guide 9 is somewhat wider than the tape so that by adjusting the member 27 the tape may be caused to run in contact with either the side 25 of the groove 21 or the opposite side as may be desired, the effect being to lay the tape directly alongside the folded margin, as shown in Fig. 2, or spaced from it.

75 As has been stated, the hammer or presser 11 and anvil 13 grip the material and feed it along. In order that the feeding of the material may start before the forward edge of said material has reached the hammer or presser, there is provided a resilient feed member 33 which is carried by the hammer and is located so as to hold the tape and the button fly against the anvil 13, said feed member being arranged to be brought down upon the tape close to the rear edge of the lower leg of the U-shaped creaser and guide 9. This auxiliary feed member 33 is shown and described more in detail in the patent which has been referred to above.

80 In the operation of the machine the end of a button fly with the end of the tape in proper position thereon is inserted in the machine, the end of the button fly and of the tape extending slightly beyond the rear 85 edge of the lower leg of the cold-creaser and tape-guide 9. Power is then applied to the machine whereupon the margin of the leather is folded, the tape laid along said margin, and both the fold and the tape 90 pressed by the hammer 11, it being understood that when the hammer is rocked forwardly and downwardly it presses against the anvil 13 both the margin of the button fly and the tape the operative face of the 95 hammer overhanging the folded margin and extending across on to the tape.

100 After the tape has been laid along that margin of the button fly in which the button holes are subsequently to be formed it is cut 105 off. The folding alone is then continued.

110 Referring now to Fig. 4 the invention is illustrated as embodied in a folding machine of the type shown in United States patent to Drake and Folsom No. 727,313. 115 The table or bed for supporting the stock is indicated at 2, the stock being fed along by two jaws 4 and 6 which are oscillated in unison about pivots (not shown) located respectively above and below the table 2. The 120 turning over of the margin is accomplished by feeding the margin past a stationary folder or horn 8, with which the edge of the stock contacts. After the margin has been turned over in this manner a spring 125 presser 10 descends and presses the fold. For a detailed description of the mechanism which has been briefly outlined above reference is made to the Patent No. 727,313, referred to above. It will be understood, how- 130

ever, that the stock is fed intermittently by the oscillating feed jaws 4 and 6 and that the margin is progressively folded over and pressed down.

- 5 In order to feed a piece of tape and lay it in the position indicated in Fig. 2 simultaneously with the folding operation a rod 12 is fastened to the head 14 of the machine and has at its lower end a portion bent at 10 right angles and formed with a slot 16 to serve as a guide to direct the tape 200 into proper position. In order to feed the tape with the stock to the jaws 4 and 6 have co-operating extensions 104 and 106 to grip 15 said tape with the stock and carry it along. A supplementary guide 18 similar to the guide 27 shown in Fig. 1 is attached to the head 14 and receives the tape from the reel (not shown).
- 20 In the operation of this machine the forward end of a button fly with the end of the tape laid upon it is placed between the open jaws 4 and 6 and their extensions 104 and 106, and power is applied to the machine. 25 The jaws 4 and 6 feed the button fly and tape along the margin of said button fly being turned over by the horn or folder 8, after which the presser 10 descends and presses the fold and the tape simultaneously. 30 A portion of a button fly 100 with the margin folded and pressed, and a portion of the tape 200 also pressed into place are shown in Fig. 4.

Although the invention has been set forth 35 in connection with certain folding machines it should be understood that the invention is not limited in the scope of its application to the particular machines shown and described.

40 Having thus described my invention what I claim and desire to secure by Letters Patent of the United States is:

1. A machine of the class described having, in combination, a support for a piece of 45 pliable material, mechanism for feeding said material over said support and for folding and pressing the margin, and a stationary member for guiding a piece of tape into position inside of and adjacent to but without 50 the plies of said folded margin whereby the tape is pressed simultaneously with the pressing of the margin.

2. A machine of the class described having, in combination, mechanism for folding 55 the margin of a piece of pliable material, means for applying to said material along said folded margin a piece of tape and means whereby said applying means may be adjusted to vary the distance of said tape 60 from said margin while maintaining the width of the fold unchanged.

3. A machine of the class described having, in combination, a support for a piece of 65 pliable material, mechanism for feeding said material over said support and for

folding and pressing the margin, said mechanism including a presser the acting face of which, when the presser is in operative position, overhangs the fold, and a stationary member for guiding a piece of tape alongside 70 the margin to be folded but in such manner as to lie without the plies of the fold into position beneath the overhanging portion of the presser.

4. A machine of the class described having, in combination, mechanism for progressively folding the margin of a piece of pliable material, said mechanism including a creaser for determining the line of fold and a presser for pressing the fold, and 75 means associated with said creaser for guiding a piece of tape into position beside said folded margin, said presser being adapted to engage said tape and press it into place.

5. A machine of the class described having, in combination, mechanism for progressively folding the margin of a piece of pliable material, said mechanism including a creaser for determining the line of fold and a presser for pressing the fold, said 80 creaser being formed with a guideway to receive a piece of tape, and means for feeding said tape with said material.

6. A machine of the class described having, in combination, mechanism for progressively folding the margin of a piece of pliable material, said mechanism including a creaser for determining the line of fold and a presser for pressing the fold, said creaser being formed with a guideway to receive 95 a piece of tape, said guideway being of greater width than said tape, means for feeding said tape with said material, and means for delivering said tape to said guideway in different relations thereto so as to vary the 100 distance from the margin at which the tape is applied to the material.

7. A machine of the class described having, in combination, a support for a piece of material having a folded margin, means 110 for feeding said piece together with a piece of tape over said support, a stationary member for guiding said tape alongside but without the plies of said folded margin, and means for pressing said tape against said 115 material.

8. A machine of the class described, having in combination, a support for a piece of pliable material, mechanism for feeding said material over said support and for folding 120 and pressing the margin, and a stationary member for guiding a reinforcing element into position inside of and adjacent to but without the plies of said folded margin whereby the element is pressed simultaneously with the pressing of the margin.

9. A machine of the class described, having in combination, mechanism for folding the margin of a piece of pliable material, means for directing upon said material 130

1,338,000

4
along said folded margin a reinforcing element, and means whereby said directing means may be adjusted to vary the distance of said element from said margin while maintaining the width of the fold unchanged.

In testimony whereof I have signed my

name to this specification in the presence of two subscribing witnesses.

WILLIAM P. CLIFFORD.
